UNITED STATES PATENT OFFICE.

JOSEPH E. SMITH AND AUGUST J. MESSLER, OF BUFFALO, NEW YORK.

DESIGN FOR A BADGE OR SIMILAR ARTICLE.

SPECIFICATION forming part of Design No. 30,388, dated March 28, 1899.

Application filed March 1, 1899. Serial No. 707,412. Term of patent 3½ years.

To all whom it may concern:

Be it known that we, JOSEPH E. SMITH and AUGUST J. MESSLER, citizens of the United States, residing at Buffalo, in the county of Erie and State of New York, have invented and produced a new and original Design for a Badge, Button, or Similar Article, of which the following is a specification, reference being had to the accompanying drawing, forming a part thereof.

This design relates to the configuration and ornamentation of a badge, button, or similar article.

The accompanying drawing is a face view 15 of a badge or button embodying our design.

The leading feature of our design consists of the representation of a frying-pan containing on its circular part the representation of a terrestrial globe showing the western 20 hemisphere.

Referring to the drawing, A represents the

circular part, and B the handle part, of the representation of a frying-pan.

C is the representation of a terrestrial globe, showing the western hemisphere and placed 25 on the circular part A.

D is the representation of an eagle, located at the junction of the handle part with the circular part.

E is the representation of the head of a 30 buffalo, arranged on the end portion of the handle part.

What we claim is—

The design for a badge or similar article, substantially as herein shown and described. 35

Witness our hands this 25th day of February, 1899.

JOSEPH E. SMITH.
AUGUST J. MESSLER.
